DEEP FAT FRYER OR THE LIKE

Frederick W. Perl and Wallace H. Appel, Mansfield, Ohio, assignors to Westinghouse Electric Corporation, a corporation of Pennsylvania

Application September 17, 1953, Serial No. 26,851

Term of patent 14 years

(Cl. D81—10)

To all whom it may concern:

Be it known that we, Frederick W. Perl, a citizen of the United States, residing in Mansfield, in the county of Richland and State of Ohio, and Wallace H. Appel, a citizen of the United States, residing in Mansfield, in the county of Richland and State of Ohio, have invented a new, original, and ornamental Design for a Deep Fat Fryer or the like, of which the following is a specification, reference being had to the accompanying drawing, forming a part thereof, in which:

Fig. 1 is a perspective view of a deep fat fryer or the like, embodying our new design;

Fig. 2 is a side elevation of the fryer shown in Fig. 1; and

Fig. 3 is a top plan view of Fig. 2 on a reduced scale.

The essential features of the design reside in the portions shown in full lines.

We claim:

The ornamental design for a deep fat fryer or the like, substantially as shown and described.
